UNITED STATES PATENT OFFICE

FRANS O. ALBERTSON AND GUSTAV OLSEN, OF SIOUX CITY, IOWA, ASSIGNEES TO
ALBERTSON & COMPANY, INC., OF SIOUX CITY, IOWA, A CORPORATION OF IOWA

ABRASIVE DEVICE

Application filed April 18, 1927. Serial No. 184,476.

The present invention relates to improvements in abrasive devices, being more particularly concerned with grinding wheels which are adapted to be used for smoothing and polishing operations.

One of the objects of our invention is the provision of an abrasive wheel having a padded rim with a longitudinal slit therein, which is adapted to permit the application of an abrasive band about said rim, with the ends of the band projecting inward toward the hub of the wheel, together with an effective tightening device for said band, adapted to permit the quick substitution of a new abrasive band with a minimum expenditure of time and labor.

Another object of our invention is the provision of an abrasive wheel of the class described, having a simple and effective band tightening device, comprising means for holding the ends of the band about a clip, resilient clamping means for clamping the folds of said band on said clip, a tightening yoke, and a pivotal connection between said yoke and clip to permit the uniform tensioning of the band upon the wheel.

Another object of our invention is the provision of an abrasive wheel of the class described, which is light, well balanced, durable, and which can be economically manufactured.

Other objects and advantages of our invention will appear more fully from the following description and from the accompanying drawings, in which similar characters of reference indicate similar parts throughout the several views.

Fig. 1 is a side, elevational view of our abrasive wheel.

Fig. 2 is a cross sectional view taken on the line 2—2 of Fig. 1.

Fig. 3 is a detail view, in perspective, of the clip employed in fastening the ends of the band.

Fig. 4 is a detail view, in perspective, of the resilient clamp employed with said clip.

Fig. 5 is a similar view of the fastening pin.

Referring to Figs. 1 and 2, 10 indicates, in its entirety, our abrasive wheel which comprises a cast metal wheel 11 having a sub-

stantially cylindrical rim 12, a hub 13, and a web 14 connecting the hub and rim.

The web 14 is preferably not centrally disposed between the edges of the rim 12 in order to provide convenient space for a tightening yoke 15 supported upon the hub 13, and the rim 12 is provided with a longitudinal slot 16 of sufficient width to permit the passage of two layers of thickness of any abrasive band which may be used with the wheel.

The exterior surface of the rim 12 is covered with a layer of heavy felt 17 comprising a band of felt of a width equal to the width of the rim and of a length sufficient to extend from one edge of the slot 16 about the rim of the wheel to the opposite edge of the slot 16.

The felt band 17 is tightly stretched about the rim 12 and secured thereto by a plurality of rows of rivets 18 passing through the felt 17 and rim 12 and tightly drawn up by the riveting operation so that the heads 19 of the rivets are depressed in the surface of the felt. The opposed upper corners 22 of the felt strip 17 may be rounded off in order to present a rounded surface, about which the abrasive band may be bent.

The web 14 is preferably cut away adjacent the inside edge of the rim 12 at the slot 16 to provide an aperture 20 for the reception of the abrasive band tightening device. In order to balance the wheel dynamically, a plurality of other apertures 21 may be made as required in the web, removing sufficient thereof to substantially balance the wheel when the tightening device of relatively heavier metal is supported thereon.

The wheel 11 is preferably constructed of cast aluminum in order to provide a very light wheel which is capable of being operated at extremely high rotative speeds and which may be used, if desired, upon apparatus which is supported by hand.

The hub 13 is provided with an axial bore 23 and the hub is preferably formed of greater length upon that side of the web which is toward the center of the rim or wheel forming a boss 24, in order to support the tightening yoke 15. The boss 24 may be provided with flat sides 25 in planes on each side.

of the boss which are parallel to the plane passing through the axis of the wheel and the slot 16.

The yoke 15 comprises a cast aluminum member of substantially U-shape, having a pair of legs 26 of substantially rectangular cross section and adapted to fit upon the flat sides 25 of the boss 24, to be supported thereon for sliding movement. The juncture of the legs 26 on the yoke 15 may be enlarged to form a head 27, providing an additional thickness for the yoke about a threaded bore 28. The bore 28 is adapted to receive a threaded bolt 29 having a non-circular head 30 which is preferably hexagonal, to permit the application of a wrench in any position of the head.

The ends 31 of the legs 26 on the yoke may be inwardly turned to provide a stop, limiting motion of the yoke in one direction upon the boss 24, and the inside of each end of the yoke may be curved to fit the contour of the adjacent part of the hub. The ends 31 of the legs 26 also project parallel to each other above the aperture 20 in the rim, the spacing of the ends 31 being sufficient to receive between them the resilient clamping member 32 and clip 33 of the fastening device.

The length of the boss 24 is preferably equal to the thickness of the yoke so that the upper surfaces of the boss 24 and the yoke coincide, and the yoke may be retained upon said boss by a washer 34 secured upon the same by a hollow bolt 35 having a head 36. The hollow bolt 35 may have a threaded bore 37 in such manner that the bolt and bore may provide a convenient fastening means for clamping the hub upon any actuating member such as a shaft.

The web 14 may also be provided with a slightly projecting concentric boss 55 about the boss 24 which is adapted to provide a guide for the yoke 15.

The abrasive means employed with our wheel preferably consists of a band 38 of paper or fabric, such as emery cloth or sandpaper, preferably the former, having its exterior surface covered with a multiplicity of sharp, projecting grains. The band 38 passes about the entire rim 12 upon the layer of felt 17, having both ends projecting inward at the slot 16 where they are secured to a fastening device further to be described. The band employed is preferably of the same width as the rim of the wheel but may be of a greater width if desired.

The fastening device for the ends of the band 38 comprises a clip 33, shown in detail in Fig. 3, a resilient clamp 32, shown in detail in Fig. 4, and a pin 39, shown in Fig. 5.

The clip 33 comprises a flat sheet of metal, preferably steel which is bent back upon itself to form a double layer, as at 40, after which the upper ends of the plate are again folded back in substantially U-shape, forming down-

wardly turned flanges 41. The flanges 41 are spaced from the double layer 40 a distance sufficient to receive a single layer of the abrasive band and the lower end of the double layer is provided with an aperture 42 adapted to receive the pin 39. The metal on either side of the aperture 42 may be cut away, as at 43, to reduce the weight of the clip and to remove parts thereof which might interfere with the web 14 of the wheel.

The resilient clamp 32 comprises a sheet metal member, preferably constructed of spring steel which is bent back upon itself, as at 44, forming two parallel flanges 45 which are spaced sufficient to receive the lower end of the double layer 40. The flanges 45 are then bent outwardly, as at 46, curved in, as at 47, and finally curved outward, as at 48, at their edges to provide a resilient clamp which will fit upon the clip 33, having fingers 49 upon each side of the clip which are adapted to press against the same.

The flanges 45 are likewise provided with an aperture 50 which is adapted to register with the aperture 42 of the clip when in assembled relation and to receive the pin 39. The thickness of the combined clamp and clip at its lower end, adjacent the apertures 42 and 50, is slightly less than the distance between the ends 31 of the yoke, and the ends 31 of the yoke are likewise provided with an aperture 51 which may be made to register with the apertures 42 and 50. The pin 39 may then be passed through the ends of the yoke, as well as the resilient clamp 32 and the clip 33, thereby pivotally fastening these members together, the pin being retained in such position by the shearing force placed on the pin when the tightening device is drawn up.

The pin 39 comprises an ordinary steel pin, having a knurled head 53 for convenient gripping by the fingers and a rounded end 54 which is adapted to aid in its insertion through the fastening device.

The assembly of the foregoing parts is as follows:

The abrasive band 38 may be formed into substantially cylindrical shape with its ends inwardly turned as they would be disposed in the slot 16. Each end of the band is then folded upward and placed between the downwardly turned flanges 41 and the body of the clip 33.

The band 38 will then have its end disposed in the clip 33, the band being folded upward about the end 52 of the flange 41 in position to pass out at the slot 16 of the wheel. With both ends of the band disposed in this position, the resilient clamp 32 is forced upon the clip 33, the fingers 49 pressing the folds of the band 38 against the flanges 41. The resilient clamp 32 having been adjusted with its aperture 50 aligned with the aperture 42 of the clamp, the inwardly turned ends of the

band 38 may be slid laterally into the slot 16, and at the same time the balance of the band will easily slide about the felt covered rim 12 of the wheel.

5 The bolt 29 in the head 27 of the yoke may be withdrawn until the yoke is moved toward the fastening device so that the aperture 51 in the yoke may be aligned with the apertures 42 and 50 of the fastening device. The pin 39 may then be passed through the ends of the yoke, the resilient clamp and the clip, thereby pivotally fastening these parts together, and the band 38 may be tightened by screwing in the bolt 29.

10 15 The bolt 29 will bear against the boss 24, forcing the yoke downward, in Fig. 1, and drawing inward both ends of the band 38, thereby tightening the same upon the rim of the wheel.

20 It will be observed that the pivotal connection between the yoke and the fastening device on the ends of the band 38 acts like an equalizer in drawing in both edges of the abrasive band equally.

25 30 The resilient clamp and the clip provide a simple and effective fastening means for the ends of the abrasive band by simply folding such ends about the flanges of the clip and pressing them against said flanges. This fastening device requires no holes in the abrasive band, nor any bolts nor screws to fasten the ends of the abrasive band.

35 The employment of a simple pin connection between the yoke and fastening device likewise enables the detachment of these parts without the application of special tools, and the only point at which a wrench or tool must be employed is in the operation of the bolt 29 which tightens the band.

40 45 The narrow slot 16 likewise tends to press the adjacent portions of the band 38 against the flanges 41 when these parts are tightened, and the narrowness of the slot also renders the rim of the wheel practically continuous.

50 It will thus be observed that we have invented an abrasive wheel which is well balanced, light and durable, and which comprises a fastening device for an abrasive band which is readily and quickly detachable for the substitution of a new band without loss of time or labor.

55 Our tightening device is also adapted to draw in both edges of the band with equal force, thereby uniformly stretching the band upon all parts of the rim of the wheel.

60 While we have illustrated and described a specific embodiment of our invention, many modifications may be made without departing from the spirit of the invention, and we do not wish to be limited to the precise details of construction set forth but desire to avail ourselves of all changes within the scope of the appended claims.

We claim:

65 1. In an abrasive device, the combination

of a metal wheel comprising a hub, a rim, and means supporting said rim on said hub, said rim having a longitudinal slot through the same, with an abrasive band extending about said rim and having its ends projecting through said slot, securing means for the ends of said band, and tightening means comprising a yoke slidably engaging said hub, a screw bearing on said hub and a removable pin pivotally connecting said yoke and securing means.

70 2. In an abrasive device, the combination of a metal wheel comprising a hub, a rim, and means supporting said rim on said hub, said rim having a longitudinal slot through the same, with an abrasive band extending about said rim and having its ends projecting through said slot, securing means for the ends of said band, tightening means comprising a yoke slidably mounted on said hub, a screw bearing on said hub and a removable pin pivotally connecting said yoke and securing means, and a threaded member extending into said hub and having a head retaining said yoke on said hub.

75 80 85 90 95 100 3. In an abrasive device, the combination of a wheel having an abrasive band about its rim and extending through a slot in said rim with means for securing one end of said band, means for securing the other end of said band comprising a sheet metal member having a backwardly turned flange, said end passing over said flange, bending about the end thereof and lying between said flange and member, a spring clip clamping said band against said flange, and means for tightening said band.

105 110 115 120 125 130 4. In an abrasive device, the combination of a wheel having an abrasive band about its rim and extending through a slot in said rim with means for securing one end of said band, means for securing the other end of said band comprising a sheet metal member having a backwardly turned flange, said end passing over said flange, bending about the end thereof and lying between said flange and member, a spring clip clamping said band against said flange, and means for tightening said band comprising a yoke passing about a hub on said wheel, a screw bearing against said hub, and a pin passing through the ends of said yoke and said sheet metal member and spring clip.

5. In an abrasive device, the combination of an abrasive band and means for removably securing the ends of said band to a tightening device, said means comprising a sheet metal member bent back upon itself and having short flanges bent back from each end in opposite directions, said flanges being spaced from said metal member to receive the ends of said band, each end of said band being located between a flange and the body of said sheet metal member, and being folded about the end of a flange extending in

the opposite direction from said flange, and removable clamping means for holding said band folded about said flanges.

6. In an abrasive device, the combination
5 of an abrasive band and means for remov-
ably securing the ends of said band to a tight-
ening device, said means comprising a sheet
metal member bent back upon itself and
10 having short flanges bent back from each end
in opposite directions, said flanges being
spaced from said metal member to receive
the ends of said band, each end of said band
being located between a flange and the body
15 of said sheet metal member, and being folded
about the end of a flange extending in the
opposite direction from said flange, remov-
able clamping means for holding said band
folded about said flanges, and means for con-
necting said first-named means to a tight-
20 ening device comprising a pin loosely passing
through said sheet metal member, clamping
means and device.

7. In an abrasive wheel, the combination
25 of a wheel having a hub, rim and means
to join said hub and rim, said rim having
a longitudinal slot, with an abrasive band
about said rim with its ends passing through
said slot, a band tightening device slidably
30 mounted on said hub, and a quick detach-
able connection between the ends of said
band and said device, said connection includ-
ing means for folding the ends of the band
about a securing member, and resilient means
35 to hold said ends in folded condition.

8. In an abrasive device, the combination
35 of a slotted support having a hub with an
abrasive band about said support and ex-
tending into said slot, means for tightening
said band about said support comprising a
40 member slidably engaging about said hub,
and a separate spring clip detachably se-
cured to said member and adapted to receive
backwardly turned ends of said band to re-
ceive the same to said member.

45 9. In an abrasive wheel, a securing device
comprising a metal member formed with a
pair of backwardly extending flanges spaced
from the body of said member to receive the
ends of a band folded about said flanges, and
50 resilient means carried by said body for press-
ing said band about said flanges.

In witness whereof, we hereunto subscribe
our names this 14th day of April, 1927.

FRANS O. ALBERTSON.
GUSTAV OLSEN.
